(57) **CLAIM**

The ornamental design for a bread slicing guide, as shown and described.

DESCRIPTION

FIG. 1 is a front, left, top perspective view of a bread slicing guide, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded view thereof; and,

FIG. 10 is an enlarged view of detail 10 in FIG. 9.

The dashed broken lines in the figures are for the purposes of illustrating portions of the bread slicing guide and form no part of the claimed design.

The dash-dot-dash broken lines are for notating enlarged views and form no part of the claimed design.

1 Claim, 10 Drawing Sheets
